Primary Examiner — Ricky Pham(74) *Attorney, Agent, or Firm* — Brooks Kushman P.C.(57) **CLAIM**

The ornamental design for the lid for food storage container, as shown and described.

DESCRIPTION

FIG. 1 is an upper rear elevation view of a lid for food storage container;

FIG. 2 is a top plan view thereof;

FIG. 3 is a side elevation view thereof;

FIG. 4 is a front elevation view thereof;

FIG. 5 is a side elevation view thereof opposite the view in FIG. 3; and,

FIG. 6 is a rear elevation view thereof.

The broken lines in the drawings as shown in FIGS. 1-6 are directed to portions of the food storage container that are not considered part of the claimed ornamental design.

1 Claim, 6 Drawing Sheets(56)
